UNITED STATES PATENT OFFICE.

CHESTER A. HOWARD, OF BROOKLYN, NEW YORK.

DESIGN FOR A PIN, BADGE, FLAG, OR SIMILAR ARTICLE.

55,564.

Specification for Design.

Patented June 29, 1920.

Application filed November 13, 1918. Serial No. 262,403. Term of patent 3½ years.

To all whom it may concern:

Be it known that I, CHESTER A. HOWARD, a citizen of the United States, and a resident of the city of New York, borough of Brooklyn, in the county of Kings and State of New York, have invented a new, original, and ornamental Design for a Pin, Badge, Flag, or Similar Article, of which the following is a specification, reference being had to the accompanying drawing, forming part thereof.

The figure is a front elevation of a pin, badge, flag or similar article showing my new design.

I claim:

The ornamental design for a pin, badge, flag, or similar article, as shown.

CHESTER A. HOWARD.
